UNITED STATES PATENT OFFICE

2,507,179

CUSHION AND CARPET STRETCHER

George S. Vnak, Minneapolis, Minn.

Application September 3, 1946, Serial No. 694,557

1 Claim. (Cl. 45—138)

1

My invention relates to improvements in fabric stretchers and has for its object to provide a simple and highly efficient stretcher for drawing taut the adjacent edge portions of two pieces of fabric in a cushion or two pieces of carpet material to be connected by sewing.

To the above end the invention consists of the novel devices and combination of devices herein-after described and defined in the claim.

In the accompanying drawing, which illustrates the invention, like characters indicate like parts throughout the several views.

Referring to the drawing:

Fig. 1 is a view looking at the back of a cushion to which the improved stretcher is applied;

Fig. 2 is a top view of the parts shown in Fig. 1;

Fig. 3 is a view looking at the inner side of the left hand terminal head of a fragment of the attached frame;

Fig. 4 is a view looking at the inner side of the right hand terminal head and a fragment of the attached frame;

Fig. 5 is a detail view principally in section taken on the line 5—5 of Fig. 4, and

Fig. 6 is a view looking at the outer side of the right hand terminal head and a fragment of the attached frame.

In order to show the improved stretcher applied in working position, there is illustrated in the drawing a cushion 7 looking at the rear end panel 8 thereof. An upper welt 9 is stitched to the cushion 7 at the seam 10 between the top sides, front and back panels thereof, a lower welt 11 is stitched to the cushion 7 at the seam between the bottom sides and the front and back panels thereof.

It is well known that in making a cushion and in filling or stuffing the same, that the entire cushion is sewed on a machine except for the seam 10 which is left open and later sewed by hand. In stuffing a cushion the filling is placed in a box of well known construction, and the filled box inserted into the cushion through the open back thereof. Next the stuffing is held in the cushion and the box removed. Finally the seam 10 is closed by hand sewing.

When closing the seam 10 by hand sewing it is very difficult to hold the edge portions of the top and back panels together and at the same time hold the same stretched taut. If the fabric is not stretched taut longitudinally the fabric will be puckered and uneven thereby giving the work an unfinished and unprofessional-like appearance.

2

By the use of my stretcher the goods at the seam 10 is stretched longitudinally and at the same time the folded edges of the goods is held close together thus greatly facilitating the sewing of the seam 10.

Referring now in detail to the present invention the numeral 12 indicates a long yoke-like frame the arms 13 of which are relatively short. On the outer end portions of the right hand arm 13 is a terminal head 14 and on the outer end portions of the left hand arm 13 is a terminal head 15. The arms 13 overlap the inner sides of the terminal heads 14 and 15 and said heads are rigidly secured to the arms 13 by welding or otherwise. It is important to note that the terminal heads 14 and 15 project outwardly of the arms 13 and form longitudinal extensions thereof.

The terminal head 14 has a large transverse 20 round hole 16 and leading therefrom are two radial slots 17. These slots 17 diverge on radial lines from the center of the hole 16 on opposite sides of the plane of the frame 12 and each at an angle of 45 degrees from said plane.

25 A long chain 18 extends through the hole 16 and is attached at its inner end to a hook 19. Said chain 18 at its other end is attached to the respective arm 13, as indicated at 20. Formed in the outer face of the terminal head 14 is an annular lock channel 21 concentric with the hole 16.

It may be here stated that each link in the chain 18 is formed of a single piece of flat metal folded upon itself. The end portions of the links 35 have therein coincident longitudinal slots. The folded end of the link is shaped to afford an eye.

The links of the chain 18 are connected by inserting one of the members of each link through the slots in the adjacent link to bring the edges 40 of the first noted link in said slots and thereby interlock the two links.

A second hook 22 is attached to an eye-bolt 23 that extends through a hole 24 in the terminal head 15 from the inside thereof. Applied to the 45 eye-bolt 23 is a thumb-nut 25 that impinges the terminal head 15 at its outer face, as a base of resistance.

To apply the improved stretcher to the cushion 7, the frame 12 is laid on the top of the cushion 7 transversely thereof, with the arms 13 extending toward the back of said cushion. The hook 22 is then inserted through the fabric of the cushion 7 at the upper rear left hand corner thereof. Next the hook 19 is inserted through the fabric of the 55 cushion at the upper right hand corner thereof.

At this time the chain 18 is loose in the hole 16. It will thus be seen that the cushion 7 is anchored to the terminal head 15 by the hook 22. To stretch the cushion 7 longitudinally at the seam 10 the chain, which is attached to the cushion 7 by the hook 19 and the hook 18, is pulled outwardly through the hole 16 until the cushion 7 at the seam 10 is stretched taut. The chain 18 is then moved edgewise to place one of its links in the lowermost lock-slot 17 and then allow slack 10 in the chain 18 to pull the edge end of the next link in the chain into the lock channel 21. With one of the links of the chain 18 in the lock channel 21 the chain 18 can not release itself from the terminal head 14.

If further stretch on the cushion is desired from that accomplished by the chain, the thumb-nut 25 may be turned on the eye-bolt 23.

The purpose of providing the stretcher with two lock slots 17 is to permit the frame 12 to be 20 placed on the cushion 7 either side up so that the lowermost lock slot can be used.

From what has been said, it will be understood that the device described is capable of modifications as to details of construction and arrangement within the scope of the invention herein disclosed and claimed.

What I claim is:

In a device of the class described, a yoke-like body member formed of a single bar having a long intermediate portion and short arms each pro-

vided at its outer end with a terminal head, a grapple on one of the terminal heads, a long link chain extending endwise through an aperture in the other terminal head for endwise sliding movement and having on its inner end a grapple, the last noted terminal head having a lock notch leading from the aperture therein into which one of the links in the chain may be inserted by a lateral movement of the chain to anchor the same to the respective arm.
